NILS H. ANDERSON, OF MIDDLETOWN, CONNECTICUT, ASSIGNEE TO THE NOISELESS TYPEWRITER COMPANY, OF MIDDLETOWN, CONNECTICUT, A CORPORATION OF CONNECTICUT.

TYPE-WRITING MACHINE.

1,162,434.

Specification of Letters Patent. Patented Nov. 30, 1915.

Application filed April 22, 1910. Serial No. 556,964.

To all whom it may concern:

Be it known that I, NILS H. ANDERSON, a citizen of the United States, residing at Middletown, in the county of Middlesex and State of Connecticut, have invented certain new and useful Improvements in Type-Writing Machines, of which the following is a full, clear, and exact description, such as will enable other skilled in the art to which it appertains to make and use the same.

The present invention relates to line-spacing mechanism for typewriting machines, and has for its object to provide a practical device of that character which shall embody a small number of parts, be cheap and easy to make and assemble.

A special object of the invention is to make the operation as noiseless as possible and to provide improved mechanism for spacing the platen roller different numbers of lines, as desired.

In the accompanying drawing, wherein is shown one of various possible embodiments of my invention, Figure 1 is a front elevation of a part of a typewriting machine with one form of the invention applied thereto; Fig. 2 is an end elevation of the same; Fig. 3 is a smaller detail view showing the platen roller immediately after the same has been line spaced and before the line space lever has been released; Figs. 4, 5 and 6 are detail sectional views of different parts of the mechanism taken on the lines $x-x$, $y-y$ and $z-z$ respectively of Fig. 1; Fig. 7 is a detail view of the platen release lever.

Similar reference characters refer to similar parts throughout the different views of the drawing.

While this invention is illustrated and will be hereinafter described with reference to that form of typewriting machine known as the noiseless typewriter, it is to be understood that it may be applied to other forms of typewriting machines.

Referring to these drawings in detail, 1 represents an end plate of the carriage frame carrying a paper carrier in the form of a platen roller 2 provided with a flat steel platen 3 rigidly secured to and extending between the end plates 1 of the frame against which the types (not shown) co-act. This platen roller 2 is provided with an axle 4 extending to one side thereof for carrying the usual hand roller 5. Mounted on this axle 4, preferably outside of the

carriage frame, is a ratchet wheel 6 provided with peripheral and crown teeth 7 and 8 engaged respectively by a platen detent 9 and a line spacing actuator 10; the former of which will be herein described more in detail. This actuator 10 is in this embodiment a pawl pivotally mounted upon a line spacing lever 11, which in turn is pivotally mounted on the frame. The pivotal connection between the actuator 10 and the line spacing lever 11 is shown in detail in Fig. 4. A stud 12 provided with a head 13 enters the line spacing lever 11 and is provided with an enlarged portion 14 about which the actuator 10 turns. Intermediate the side of the actuator and the head of the screw is a resilient cup shaped washer 15 holding the actuator in frictional engagement with the line spacing lever, whereby as the lever 11 is moved toward the platen roller the actuator 10 will be carried immediately into contact with the crown ratchet teeth 8 on the ratchet wheel to rotate the same in a line spacing direction. When the line spacing lever is released to permit its return to normal position, the actuator, which is in frictional engagement therewith, is immediately carried out of contact with the ratchet teeth in order to avoid a disagreeable and noisy clicking of the pawl over the teeth, as is common in many typewriting machines.

The actuator and line spacing lever are guided and limited in their return movement to normal position by a stationary L-shaped cam arm 16 rigidly secured to the frame and extending to one side of and parallel to the plane of movement of the actuator, and which is engaged by a pin 17 carried by the actuator. This arm not only limits the return movement of the line spacing lever, but also returns the actuator along a line parallel with the plane of the ratchet teeth and holds the same closely adjacent but out of contact with the ratchet wheel so that it may immediately engage therewith when the device is actuated.

Pivotal connection between the line spacing lever and the frame of the machine is shown in a detail sectional view in Fig. 6. A stud enters the frame at 18 and is provided with a central enlarged portion 19 and a slotted head 20. About the enlarged portion of this pin is a bushing 21 with an outer flanged end; about the bushing is

mounted the line spacing lever 11 having an annular chamber in which is a spiral spring 22. One end of this spring engages the line spacing lever while the opposite end is connected with the hexagonally flanged head of the bushing 21 (see Fig. 1); the spring is so tensioned as to return the line spacing lever to normal position after it is actuated. This construction permits a ready adjustment of the spring in the following manner: A screw driver is inserted in the slotted head 20 and turned to loosen the threaded connection between the pin and the frame, after which the bushing 21 may be turned by means of a wrench engaging the hexagonal head, thereby increasing or diminishing the tension of the spring 22. As soon as the desired tension is obtained the screw head is tightened, firmly clamping the bushing in adjusted position between the frame and the head. The bearing sleeve of the line spacing lever is preferably constructed slightly shorter than the sleeve of the bushing 21 in order to have a free rotary motion thereabout when the sleeve is clamped in position.

The actuator 10 carried by the line spacing lever is provided at one side with a curved cam face or edge 23 adapted to be engaged by one arm 24 of a rotary stop 25 in the form of a bell crank lever. The opposite arm 26 carries a pin 27 engaging one of a plurality of recesses or holes 28 in the line spacing lever; (see Figs. 1 and 5). This stop turns about a stud 29 rigidly secured to the line spacing lever and having an enlarged head 30. Carried by the stop 25 is a sleeve 31 of sufficient size to receive the enlarged head 30 of the stud, thereby forming an annular chamber about the shank of the stud in which is a spring 32 bearing against the stop at one end and the inner surface of the head at its opposite end, tending to hold the stop with the pin 27 engaging one of the recesses 28 in normal position. The outer surface of the sleeve 31 is preferably knurled or roughened in order that the same can be conveniently grasped by the operator and moved in the direction of the longitudinal axis of the stud 29, whereby the pin 27 may be withdrawn from the hole 28 and moved into engagement with another to vary the throw of the actuator.

In the position shown in Fig. 1 the actuator will engage the ratchet wheel and rotate the platen roller three spaces in a line spacing direction before the projection 24 engages the cam surface 23, thereby preventing further motion, as shown clearly in Fig. 3. By rotating the stop to the intermediate position the projection 24 of the adjusting stop will engage the central portion of the cam face or edge 23 and permit the actuator to move only a sufficient dis-

tance to rotate the platen roller two line spaces before the wedging action takes place, while if the adjusting stop is moved to the third position the projection will engage the upper end of the cam surface and wedge the actuator into engagement with the ratchet wheel after the platen roller has been rotated through a single line space.

In order to insure the rotation of the platen roller through exact line spaces, a spring arm 33 is rigidly secured to the frame of the machine at 34 and carries at the upper part thereof the roller 9 engaging the peripheral notches 7 of the ratchet wheel in order to register the paper correctly at each operation. Should it be desired, however, to rotate the platen an irregular amount, as is frequently necessary in filling in blank forms, for example, the roller 9 may be thrown out of engagement with the ratchet wheel by raising an arm 35, Fig. 7, of the plate 36, shown in detail in Fig. 7, mounted on a sleeve about the axis of the platen roller and provided with two notches 37 and 38. The notch 37 is of such shape and size that when the roller 9 engages the ratchet 7, said roller and its supporting parts 38 are entirely free from and out of contact with the plate 36, the latter being yieldingly supported in this position by a spring detent 39 secured between the frame of the carriage and the spring arm 33, said detent being provided at its upper end with a notch engaging a projection 40 in the plate 36, and with a deflecting or cam surface 41 to provide for the passage of the projection 40 into the notch. The detent 39 thus provides a down stop for the plate or release lever, supporting the same out of contact with either the roller 9 or its bearings 38, and at the same time holding the release lever lightly and firmly in position, preventing the same from rattling. Furthermore, the release lever being out of contact with either the roller 9 or its frame, free action in controlling the movement of the platen through the roll 5 is permitted.

It will be noted in operation that when the line spacing lever 11 is actuated the actuator or pawl carried thereby will be moved into immediate engagement with the ratchet teeth and rotate the same a varying number of spaces, according to the position of the adjusting mechanism, before the extension or projection 24 wedges the actuator through the cam surface 23 against the ratchet teeth, thereby preventing further movement. When the line spacing lever is released the spring 22 about the pivotal connection with the frame will immediately carry the same to normal position, and the frictional contact between the actuator and the line spacing lever will move the former out of engagement with the ratchet teeth to prevent noise. The arm 16 on the

frame of the machine will not only guide and limit the movement of the movable parts in their return to normal position, but will also be silent and positive in its action.

5 As many changes could be made in the above construction and many apparently widely different embodiments of this invention could be made without departing from the scope thereof, it is intended that all 10 matter contained in the above description or shown in the accompanying drawings shall be interpreted as illustrative and not in a limiting sense.

Having described my invention, what I 15 claim as new and desire to secure by Letters Patent is:

1. In a line spacing mechanism for type-writing machines, in combination, a paper carrier, a ratchet thereon, a line spacing lever, an actuator pivotally mounted on said 20 line spacing lever intermediate the ends thereof adapted to be carried into engagement with said ratchet when the line spacing lever is actuated, and stationary means 25 adapted to engage said actuator and hold said actuator adjacent and out of contact with said ratchet and to limit the return movement of said lever by its engagement with the pawl.

30 2. In a line spacing mechanism for type-writing machines, in combination, a paper carrier, a ratchet thereon, a pivotally mounted line spacing lever, spring means about the pivot of said lever adapted to hold said lever in normal position, an actuator mounted intermediate the ends of said 35 lever held adjacent to but out of contact with said ratchet, and means intermediate the actuator and the free end of said lever 40 for varying the throw of said actuator.

3. In a line spacing mechanism for type-writing machines, in combination, a paper carrier, a ratchet therefor, a line spacing lever, spring means adapted to hold said 45 lever in normal position, an actuator having a curved edge mounted intermediate the ends of said lever held adjacent to but out of contact with said ratchet, and means on said line spacing lever adapted to engage 50 different portions of said edge to vary the throw of said actuator when the line spacing lever is actuated.

4. In a line spacing mechanism for type-writing machines, in combination, a paper 55 carrier, a ratchet therefor, a line spacing lever, an actuator having a cam face mounted on said line spacing lever, means for holding said actuator in frictional engagement therewith whereby said line spacing lever and actuator move together, and means carried by said lever adapted to engage different portions of said actuator to 60 vary the throw of said actuator.

5. In a line spacing mechanism for type-writing machines, in combination, a paper

carrier, a ratchet therefor, a line spacing lever having holes therein, an actuator mounted on said line spacing lever, means for holding said actuator in frictional engagement therewith, a pivotally mounted 70 stop adapted to engage one of said holes to vary the throw of said actuator, and a spring associated with said stop for holding the same in adjusted position.

6. In line spacing mechanism for type-writing machines, in combination, a paper carrier, a ratchet therefor, a line spacing lever, an actuator mounted on said line spacing lever, spring means for holding 75 said actuator in operative frictional engagement with said line spacing lever, and means for holding said actuator adjacent to but out of contact with said ratchet.

7. In line spacing mechanism for type-writing machines, in combination, a platen 80 roller, a ratchet therefor, a line spacing lever, an actuator pivotally mounted on said line spacing lever, spring means for holding said actuator in operative frictional engagement with said line spacing lever, and 85 a stationary arm to limit the return movement of said line spacing lever.

8. In line spacing mechanism for type-writing machines, in combination, a platen 90 roller, a ratchet therefor, a line spacing lever, an actuator pivotally mounted on said line spacing lever, spring means for holding 95 said actuator in operative frictional engagement with said line spacing lever, and means adapted to hold said line spacing lever in normal position through said actuator.

9. In line spacing mechanism for type-writing machines, in combination, a paper 100 carrier, a ratchet therefor, a pivotally mounted line spacing lever, spring means about said pivot for holding said line spacing lever in normal position, an actuator 105 pivotally mounted on said line spacing lever, means for determining the throw of said actuator, and means for holding said actuator in frictional contact with said line spacing lever whereby it is withdrawn from 110 engagement with said ratchet on return movement of said line spacing lever.

10. In line spacing mechanism for type-writing machines, in combination, a carriage frame, a paper carrier, a ratchet therefor, a line spacing lever pivotally mounted on said frame, a spring for returning said line 115 spacing lever, means for varying the tension of the spring, an actuator mounted on said line spacing lever, means for holding said actuator in frictional engagement therewith, and a stop engaging said actuator 120 adapted to vary the throw of said actuator.

11. In line spacing mechanism for type-writing machines, in combination, a platen 125 roller, a ratchet therefor, a line spacing lever, spring means for holding said line

- spacing lever in normal position, an actuator mounted on said line spacing lever, and spring means associated with the connection between the actuator and the line spacing lever for holding said parts in frictional engagement whereby the actuator is withdrawn from engagement with said ratchet when the line spacing lever returns to normal position.
- 10 12. In line spacing mechanism for typewriting machines, in combination, a carriage frame, a platen roller carried thereby, a ratchet wheel on said roller, a line spacing lever pivotally supported on said frame, a pivot for said lever, a spring about said pivot, an actuator pivotally mounted on said line spacing lever adapted to be carried into engagement with said ratchet wheel when the line spacing lever is actuated, a resilient member adapted to act on said actuator and lever, whereby said actuator is withdrawn from said ratchet wheel when said lever is released, and means for line-centering said platen roller.
- 15 13. In line spacing mechanism for typewriting machines, in combination, a frame, a paper carrier, a ratchet therefor, a line spacing lever mounted on said frame, spring means adapted to hold said lever in normal position, an actuator having a curved edge pivotally mounted intermediate the ends of said lever, a pivotally mounted stop adapted to engage different portions of said actuator on said line spacing lever to vary the throw of said actuator when the line spacing lever is actuated, and means for line-centering said paper carrier.
- 20 14. In line spacing mechanism for typewriting machines, in combination, a carriage frame, a platen roller, a ratchet wheel therefor, a line spacing lever pivotally supported on said frame, an actuator pivotally mounted on said line spacing lever and held in frictional contact therewith whereby it is carried into engagement with said ratchet wheel or withdrawn therefrom when the line spacing lever is actuated, a resilient arm on said frame, and a roller carried thereby adapted to register said platen roller.
- 25 15. In line spacing mechanism for typewriting machines, in combination, a frame, a platen roller, a ratchet wheel on said roller, a line spacing lever pivotally mounted on said frame, spring means adapted to hold said lever in normal position, an actuator having a cam face pivotally mounted intermediate the ends of said lever, a pivotally mounted stop having a part adapted to engage the cam face in said actuator to vary the point of throw of said actuator when the line spacing lever is actuated, a resilient arm on said frame, and means carried thereby adapted to line-center said platen roller.
- 30 16. In line spacing mechanism for typewriting machines, in combination, a support, an adjustable sleeve secured thereto, a line spacing lever turning on said sleeve, and a return spring coacting with said sleeve and said line spacing lever
- 35 In testimony whereof I affix my signature, in the presence of two witnesses.
14. In line spacing mechanism for typewriting machines, in combination, a carriage
